DEFECTIVE-CIGAR-BUNCH DETECTOR FOR CIGAR MACHINES

Lester Ferenci, Brooklyn, N. Y., assignor to International Cigar Machinery Company, a corporation of New Jersey

Application November 22, 1935, Serial No. 51,055
Renewed March 2, 1939

19 Claims. (Cl. 131—21)

This invention relates to improvements in cigar machines, its main object being to mechanically inspect the cigar bunches and to automatically prevent application of wrappers to bunches having soft heads.

Heretofore, in the manufacture of scrap bunch cigars the bunches, after being made by hand or in a scrap bunch machine, were transferred to a soft work rolling machine wherein the bunches were concentrated or molded and wrapped and trimmed to the desired length. Since the bunches were generally transferred manually to the concentrator or bunch molding turret of the soft work rolling machine, the attendant could detect and reject the defective bunches. In the soft work rolling machine selected to illustrate one embodiment of the invention the defective bunch is detected by a yieldingly mounted pin on the bunch-ejector of the turret, this pin projecting slightly above the other ejector pins, to impinge the cigar bunch in the mold just before its cover has been removed. Upon encountering a normal bunch, the feeler pin recedes thereby opening a low-tension circuit connected to a solenoid. When the bunch is soft, the pin does not recede but presses into the bunch and maintains a position closing the circuit. Likewise, when there is no bunch in the mold the circuit is closed by the feeler pin. Somewhat later in the cycle of operations, a timing switch in the low-tension circuit makes contact for a limited time and, when the feeler switch is closed in case of a soft bunch or a missing bunch, energizes the solenoid, thereby actuating a stop-lever which prevents the suction from being cut off in the wrapper carrier and wrapper-cutting bed. The engagement of a set screw places the feeler in contact position at the end of each bunch-ejection movement, and a cam is provided to reset the stop-lever at each cycle of the machine.

Generally stated, in the particular embodiment of the invention herein illustrated an operation is performed on a cigar bunch by movable means carrying a member or members moving therewith and engaging the bunch to detect the presence of a defective bunch or the absence of a bunch. In the best constructions contemplated the bunches may be supported in an intermittently rotating bunch molding turret having an ejector provided with feelers arranged to detect a defective bunch or the absence of a bunch at the ejecting station of the turret and thereupon actuating mechanism for incapacitating the mechanism for applying wrappers to the ejected bunches. Preferably, the incapacitating mechanism interrupts the upward movement of the suction head which would otherwise present the cut wrapper to the wrapper carrier to be transported to the bunch wrapping device, and prevents the suction from being cut off from the cut-

ting bed and head and also prevents the application of suction to the wrapper carrier.

The specific structure selected to illustrate the invention is but one of many possible concrete embodiments of the same. The invention, therefore, is not to be restricted to the details illustrated and described nor to the particular embodiment chosen as illustrative of the invention, but may be widely varied in construction.

In the accompanying drawings which form a part of this specification and in which like characters of reference indicate the same or like parts:

Fig. 1 is a diagrammatic side elevation of a soft work rolling machine equipped with the automatic inspection device;

Fig. 2 is an end elevation viewed from line 2—2 of Fig. 1 on an enlarged scale;

Fig. 3 is an end elevation from line 3—3 of Fig. 1 on a similar enlarged scale; Fig. 4 is an end elevation of an alternative form of construction; and Fig. 5 is a sectional side elevation of the same taken on the line 5—5 of Fig. 4.

Referring to Fig. 1, the bunch B expelled from the bunch concentrator or molding turret 5 is carried by a bunch transfer of well known construction comprising a swinging transfer arm 6, to a bunch wrapping device 7, of conventional construction such as that shown in Patent No.

1,915,277, granted June 27, 1933, on the application of J. F. Halstead, the end positions 6' and 6'' of this transfer arm corresponding to the bunch positions B' and B''.

Meanwhile, the attendant spreads a tobacco leaf W on the wrapper die of the cutting bed 8 and a wrapper is cut therefrom in the usual manner by cutting rollers (not shown) which move across the wrapper die. The leaf is held by suction on the bed 8 while the wrapper W is being cut, and the cut wrapper is picked up by the hollow wrapper carrier 9 and transported to the bunch wrapping device 7 in the customary manner.

For this purpose the bed 8 and the wrapper carrier 9 communicate with a common suction chamber 10, and the suction in the bed and carrier is controlled by slide valves 11 and 12 respectively, the valve 11 being closed and the valve 12 opened by a cam, as will be presently described, while the wrapper is being picked up by the carrier 9.

The chamber 10 is connected to a suction conduit 13 which communicates with a suitable source of suction (not shown).

The wrapper carrier 9 may be supported in any suitable or desirable manner, for example it may have a hollow stem pivotally mounted, as shown in Patent No. 1,539,274, granted May 26, 1925, on the application of R. E.

Rundell, in a lever arm 14 having its hub mounted in the free end of a hollow arm 14a fastened on the upper end of a shaft 15. The latter may be intermittently rocked in the manner hereinafter

described, or by a cam-actuated gear sector as shown in the patent referred to above, the arm 14b of the lever 14 being provided with a roller engaging a track in a fixed cam as shown in said patent, wherefore the wrapper carrier will be moved from position 9' above the bed 8 to position 9" adjacent the wrapping device 7 in each cycle of the machine. While the carrier is in position 9' the suction head 17 of the bed 8 is raised by a cam lever as hereinafter described, to press the cut wrapper against the bottom of the carrier 9, whereupon the suction is cut off from the bed 8 and its head 17 and applied to the carrier. For this purpose, the bed 8 communicates with the suction chamber 10, and the carrier communicates through the lever 14 and arm 14a with a hollow column 16 in direct communication with the chamber, the shaft 15 being journaled in bearings provided in the chamber and column. When the carrier is at position 9" it is turned in its mounting in the lever 14 to pay off the wrapper to the bunch being wrapped in the device 7, by an arm 9b on the upper end of its stem connected to linkage controlled by the fixed cam as shown in the patent referred to above. Since the details of construction of the carrier 9 and the device 7 are well known in the art, further description thereof is deemed unnecessary. The covers 18 of the mold pockets 19 are successively removed at the ejecting station of turret 5 by mechanism (not shown) of any well known type, such as shown in the patent to R. E. Rundell, No. 1,838,157, issued December 29, 1931, provided for this purpose, and the bunch B is lifted out of the mold by a group of ejector pins 20 so arranged on a holder 21 that their tips form a cradle for the bunch. The holder 21 is attached to a head 22 mounted on a vertical slide rod 23 which is actuated by a cam lever 24 fulcrumed on a shaft 25 and having a cam roller 26 in engagement with a cam groove 27 of a face cam 28. The rod 23 slides in a bracket 29 of the machine and is guided by a pin 30 also sliding in member 29.

The transfer arm 6, which is provided with grippers 31 automatically actuated in a well known manner such as shown in the patent to J. F. Halstead, No. 1,786,608, issued December 30, 1930, for gripping and releasing the bunch, is periodically swung to and fro by a rack 32 connected to a cam lever 33 fulcrumed on a shaft 34 supported by a frame member 35. The cam lever 33 carries a cam roller 36 engaging with a second cam groove 37 of face cam 28. The suction head 17 is connected by a rod 38 to a cam lever 39 fulcrumed on shaft 25 and having a cam roller 40 held against a plate cam 41 by a tension spring 42. The valves 11 and 12 are connected by links 43 and 44 to a cam lever 45 fulcrumed on shaft 43 and 44 and having a cam roller 46 which is held against a plate cam 47 by a spring 48. The turret 5, bunch wrapping device 7 and the shaft 15 of the wrapper carrier 9 are driven through chains 49, 50 and 51, respectively, from the cam shaft 52 and thus operate in synchronism with one another. The chain 51 drives a drum cam 51a provided with a circumferential cam groove, and the shaft 15 carries a lever 15a provided with a cam roller engaging said cam groove. The turret is provided with any suitable form of intermittent device (not shown) driven by chain 49, that shown in Patent No. 1,838,157, granted December 29, 1931, on the application of R. E. Rundell, being suitable for this purpose.

In order to prevent the wrapper carrier 9 from

taking a wrapper from the suction head 17 in case there is no bunch or an imperfect bunch in the mold pocket 18 which is about to be uncovered, the ejector pin 20' adjacent the head end of the bunch is attached to a separate holder 53 (Figs. 1 and 2) mounted on an upright pin 54 slidably in lugs 55 of bracket 22 and guided by a pin 56 fixed in the holder and sliding in the upper lug 55. To pin 54 is pivotally connected an arm 57 fast on one end of a shaft 58 journaled in bearings provided in the bracket 22. Suitable yieldable means are provided for preventing rotation of the shaft 58 and thereby maintaining the pin 20' at the desired level with respect to the pins 20, comprising in the embodiment of the invention selected for illustration herein a friction disk 59, a thrust washer 60 seated against a shoulder of shaft 58 and pressed against disk 59 by a compression spring 61 seated against the bracket 22 and bearing against a nut 62 threaded on shaft 58, whereby the friction of the disk 59 against the washer 60 may be regulated. On the other or rear end of shaft 58 is loosely mounted an arm 63 carrying an insulated contact pin 64 which is held against a stationary contact rail 65 mounted on an insulating block 66 attached to frame member 29, by a tension spring 67 anchored to the hub of an arm 68 fastened on shaft 58. The arm 68 as its ends carries stop screws 69 and 70.

The pin 20' is periodically set by mechanism hereinafter described so as to contact the bunch B slightly in advance of the remaining pins 20 and just before the cover 18 of the mold 19 has been lifted, the pin 20' being maintained in this slightly advanced position by the yieldable means described above preventing rotation of the shaft 58, while the head 22 is being raised by the rod 23. When the bunch has a solid head of proper hardness, the pin 20' will be arrested by it until the remainder of the ejector pins have come in contact with the bunch, whereupon the floating holder 53 will meet the bracket 22 and all the pins will rise together. This relative motion between the holder 53 and the bracket 22 causes the arm 57 to turn the shaft 58 and, with it, the arm 68 through a small angle, thereby causing the screw 69 to raise the pin 64 off the rail 65. It will be understood that the nut 62 may be adjusted on shaft 58 to cause the pin 20' to yield for any predetermined hardness of the bunch.

But, if the bunch in mold 19 has an imperfectly filled or "soft" head, or if there is no bunch in the mold as will happen at the start and finish of a run, the feeder pin 20' will not be arrested by its contact with the bunch and all the pins will advance together as the rod 23 moves upward. There then being no relative motion between holder 53 and bracket 22, the shaft 58 will not turn and hence the pin 64 will remain in contact with rail 65.

The contact 64, 65 is part of the low-tension electric circuit of a step-down transformer 71 connected by leads 72 to high-tension supply lines 73. One terminal of the low-voltage side of the transformer is connected by a lead 74 to the pin 64, and the rail 65 is connected by the lead 75 to the stationary contact of a timer switch 76 of conventional construction, the rotary contact maker of which is mounted on cam shaft 52. A brush bearing against the hub of the rotary contact maker is connected by a lead 77 to one end of the coil of a relay 78 connected by a lead 79 to the other terminal of the low-voltage side of the transformer.

5 The timer switch 76 is set to close for a short period at a time just prior to the upward displacement of cam lever 39, which actuates the suction head 17 and which is followed by the action of cam lever 45 operating the suction valves 11 and 12. When the contact 64, 65 is closed, in case of a defective or missing bunch, the relay 73 will be energized to close the relay contacts 88, thus establishing a closed circuit 10 from one line 73 through leads 81, 82 through a solenoid 84 to the other line 73. The solenoid is thus energized and its core 85 is thereby moved in the direction of the arrow.

15 A connecting rod 86, Figs. 1 and 3, transmits this motion to an arm 87 fulcrumed on a shaft 88 in frame member 35 and carrying blocks 89 and 90 which thereupon engage with pins 91 and 92 in the horizontal arms of cam levers 39 and 45, respectively, and prevent their upward displacement by their tension springs 42 and 48 which would otherwise occur when their cam rollers 40 and 46 ride over the low portions of their cams 41 and 47. The arm 87 is provided with spaced stop screws 93 and 94 and a cylindrical boss 95, a compression spring 96 in the bore of the boss pressing a ball 97 into one of the two recesses 98 in a rib 99 extending from frame member 35 and thereby locking the arm 87 in each of its end positions wherein either of the 20 stop screws 93 and 94 abuts the adjacent side of the rib 99.

25 As the ejector pins 20 recede, and when the bracket 22 has arrived in a position 22' a small distance from its lowermost position 22'', Fig. 2, the stop screw 70 in arm 68 engages an abutment 100 on frame members 29, thus turning the arm 68 and turning the shaft 53 to raise the holder 53 to a position wherein its pin 20' will engage the next bunch, during the next upward stroke 30 of the bracket 22, slightly ahead of the pins 20. Furthermore, the screw 69 is returned to its initial position so that the spring 67 will pull pin 40 64 back into contact with rail 65, if that contact has previously been opened by a perfect bunch.

45 To the periphery of cam 28 is attached a cam piece 101, Figs. 1 and 3, which engages a roller 102 carried by an arm 103 extending from the hub of lock lever 87, in case the arm 87 has been turned into locking position by the action of solenoid 84, due to a missing bunch, or the presence of an imperfect bunch in mold 19. Thereupon the arm 103 is turned back and the lock lever 87 reset into neutral position.

50 If it is desired to "feel" the cigar bunch in more than one place, a suitable number of the ejector pins 20 are replaced by feelers similar to the head pin 20' and similarly connected to a corresponding number of separate shafts 58 equipped with contact pins 64. By then connecting all the contact pins 64 in parallel in the low-tension circuit, the current will flow through the relay 73 when any one of these pins fails to break the corresponding contact on rail 65, and the energizing of solenoid 84 will swing the stop lever 87, into locking position, thus preventing the upward motion of suction head 17 and the actuation of the valves 11 and 12 which would otherwise cut off the suction in the head 17 and apply it to the wrapper carrier.

55 As shown in Figs. 4 and 5, pins 20' and 20c may be arranged to feel the head and tuck ends respectively, of the bunch and the intermediate pins 20a and 20b are suitably spaced from each other to feel different points along the circumference of the bunch. The head end pin 20' is

60 mounted in the same manner, as described above, in a holder 53 carried by an upright pin 54 sliding in lugs 55 of the ejector bracket 22, the holder being provided with a guide pin sliding in the upper lug 55. The pin 54 is connected by the link 57 to the shaft 58 to be depressed against the friction of the friction disk 59 on the thrust washer 60, which is seated against a shoulder of shaft 58 and pressed against the disk by the axial thrust imposed on the shaft by a spring in the same 65 manner as described above, whenever the pin encounters the head end of a normal bunch. In this event the contact maker 64, which is mounted on shaft 58, is swung away from the contact rail 65 and the circuit through the same is thereby broken. The pins 20a, 20b and 20c are mounted in blocks 53a, 53b and 53c carried by pins 54a, 54b and 54c sliding in lugs 55a, 55b and 55c, respectively, and, are similarly connected by links 57a, 57b and 57c to their respective shafts 58a, 58b and 58c. These shafts are each provided with a friction disk against which a thrust washer is pressed by an axial thrust imposed on the shafts through the agency of compression springs seated against the bracket 22 and bearing against 70 nuts threaded on the shafts.

75 The contact makers 64, 64a, 64b and 64c are each carried by arms 63, 63a, 63b and 63c which are loose on their respective shafts and provided with tension springs connecting them to arms 88, 68a, 68b and 68c fastened on the respective shafts, whereby the contact makers are normally held against the contact rail. The arms 68, 68a, 68b and 68c carry adjustable stop screws at their ends. Should any of the feeler pins encounter a single or several soft spots in the bunch, or in case a bunch is missing at the ejector station of the concentrator turret, one or more contact makers will remain in circuit-closing position and the delivery of the wrapper to the wrapping 80 mechanism will be prevented in that cycle of the machine.

85 While in trade usage the term "cigar bunch" and "cigar wrapper" have a narrow technical meaning, these terms are employed herein in their broad sense, in the absence of specific language to the contrary. Thus, the term "cigar bunch" as used in the claims may refer to a charge without a binder as well as to a charge having a binder, known to the trade as a "cigar bunch." Similarly, the term "cigar wrapper" is not limited to the spirally wound outer wrapping but may refer to such binders or wrappings as constitute the sole wrapper, such as in Toscani cigars.

90 What is claimed is:

1. In a cigar machine, the combination with mechanism for applying a wrapper to a cigar bunch, of means for shaping a cigar bunch, bunch transfer instrumentalities for transporting a bunch from said means to said mechanism, and a device for detecting the absence of a bunch and the presence of a defective bunch in said means and thereupon incapacitating said mechanism.

15 2. In a cigar machine, the combination with mechanism for applying a wrapper to a cigar bunch, of means for shaping a cigar bunch, bunch transfer instrumentalities for transporting a bunch from said means to said mechanism, a device for detecting the absence of a bunch and the presence of a defective bunch in said means and thereupon incapacitating said mechanism, and means for rehabilitating said mechanism.

20 3. In a cigar machine, the combination with mechanism for applying a wrapper to a cigar 75

- bunch, of means for shaping a cigar bunch, bunch transfer instrumentalities for transporting a bunch from said means to said mechanism, a device for detecting the absence of a bunch and the presence of a defective bunch in said means and thereupon incapacitating said mechanism, said bunch shaping means including an intermittently rotating bunch molding turret, and said device including a member acting to engage the bunches in successive pockets of said turret at one station thereof and thereby detect the absence of bunches therein or the presence of defective bunches.
4. In a cigar machine having bunch shaping means, the combination with mechanism for applying a wrapper to the shaped bunch, of a device for detecting defective bunches in the shaping means, and mechanism controlled by said device for preventing the application of a wrapper to the defective bunch.
5. In a cigar machine, the combination with an intermittently rotating turret provided with a plurality of bunch molding pockets, of a member for ejecting the bunches from successive pockets of said turret, and a device carried by said member for detecting the absence of bunches in the successive pockets and the presence of defective bunches therein.
6. In a cigar machine, the combination with an intermittently rotating turret provided with a plurality of bunch molding pockets, of a member for ejecting the bunches from successive pockets of said turret, a device carried by said member for detecting the absence of bunches in the successive pockets and the presence of a defective bunches therein, mechanism for wrapping the ejected bunches, and means controlled by said device for incapacitating said mechanism when the absence of a bunch or the presence of a defective bunch is detected in one of said bunch molding pockets.
7. In a cigar machine, the combination with an intermittently rotating turret provided with a plurality of bunch molding pockets, of a member for ejecting bunches from successive pockets of said turret, and a device carried by said member for detecting the absence of bunches in the successive pockets.
8. In a cigar machine, the combination with an intermittently rotating turret provided with a plurality of bunch molding pockets, of a member for ejecting bunches from successive pockets of said turret, and a device carried by said member for detecting the absence of bunches in the successive pockets, mechanism for wrapping the bunches, and means controlled by said device for incapacitating said mechanism when the absence of a bunch is detected in one of said pockets.
9. In a cigar machine, the combination with an intermittently rotating turret provided with a plurality of bunch molding pockets, a member for ejecting the bunches from successive pockets of said turret, and a device carried by said member for detecting the presence of defective bunches in the successive pockets.
10. In a cigar machine, the combination with an intermittently rotating turret provided with a plurality of bunch molding pockets, a member for ejecting the bunches from said successive pockets of said turret, a device carried by said member for detecting the presence of defective bunches in the successive pockets, mechanism for wrapping the ejected bunches, and means controlled by said device for preventing the wrapping of a defective bunch.
11. In a cigar machine, the combination with an intermittently rotating turret provided with a plurality of bunch molding pockets, of a device for detecting the absence of a normal bunch or the presence of a defective bunch in any one of said pockets.
12. In a cigar machine, the combination with an intermittently rotating turret provided with a plurality of bunch molding pockets, of a device for detecting defective bunches in said pockets.
13. In a cigar machine, the combination with an intermittently rotating turret provided with a plurality of bunch molding pockets, of a device for detecting in said pockets bunches having soft "heads."
14. In a cigar machine, the combination with an intermittently rotating turret provided with a plurality of bunch molding pockets, of a device for detecting in said pockets bunches having soft spots along their entire length.
15. In a cigar machine, the combination with a support for a cigar bunch, of a device for detecting defective bunches in said support, said device including members spaced along the circumference of the bunch in said support to engage and thereby detect soft spots at different points on the circumference of the bunch.
16. In a cigar machine, the combination with a mechanism for wrapping cigar bunches, of a wrapper-cutting bed including a wrapper die and a vertically movable suction head within said die, a wrapper carrier for transporting wrappers from said head to said wrapping mechanism, a suction chamber communicating with said bed and carrier, means for reciprocating said head to present the wrapper to said carrier and means thereupon cutting off the suction from said head, and mechanism for detecting a defective bunch in the machine and thereupon incapacitating both of said means.
17. In a cigar machine, the combination with a mechanism for wrapping cigar bunches, of a wrapper-cutting bed including a wrapper die and a movable suction head within said die, a wrapper carrier for transporting wrappers from said head to said mechanism, means for actuating said head to present the wrapper to said carrier, and mechanism for detecting a defective bunch in the machine and thereupon incapacitating said means.
18. The combination with a carrier for transporting a cut tobacco leaf section to a predetermined position, of a cutting bed including a die for cutting a section from leaf tobacco and a suction head within said die, mechanism for raising said head to present the cut leaf section to said carrier, and means for locking said mechanism to prevent the upward movement of said head and delivery of cut sections to said carrier.
19. In a cigar machine, the combination with bunch wrapping mechanism, of means for periodically supplying wrappers to said mechanism, a bunch transfer for supplying bunches to said mechanism, and a device for detecting defective bunches and incapacitating said wrapper supplying means upon detection of a defective bunch and automatically reinstating said wrapper supplying means at a predetermined point in the next machine cycle prior to the transportation of the next bunch by said transfer.

LESTER FERENCI.
